OIL ACCELERATOR

Eugene S. Scheble, Fort Worth, Tex.

Application March 1, 1941, Serial No. 381,371

6 Claims. (Cl. 210—57)

This invention relates to the purification and acceleration of lubricating oils in internal combustion motors of the type conventionally employed in the operation of motor vehicles and aircraft, as well as stationary motors, and it has particular reference to a centrifugal device adapted to be installed in a lubricating system by connecting the same into the lubricant flow line, and its principal object resides in the provision of an assembly of parts including a reservoir for the collection of the heavy, undesirable constituents of the lubricant, such as abrasives, motor cuttings, heavy particles of carbon, and the like, which impair the lubricant as such and greatly decrease its efficiency.

Another object of the invention resides in the provision of a device of the character described which aids in the acceleration of the flow of the lubricant through the system due to the elimination of the contaminating constituents heretofore mentioned and boosting the flow in a manner similar to the action of a fuel pump.

An object of the invention is also manifest in the provision of an arrangement whereby the lubricant may be subjected to a cooling action, being brought in close contact with the atmosphere and subjected to air cooling arrangement of the motor with which it is employed, thereby greatly minimizing the normal running temperature of the oil and greatly increasing the efficiency of the motor.

Broadly, the invention seeks to comprehend the provision of apparatus embodying a mechanical arrangement whereby the impurities in the lubricating oil of an internal combustion engine may be separated out by centrifugal action applied through the movement of the oil itself flowing through the system and whereby such impurities, including water, and other foreign substances, as can be precipitated to the bottom of a reservoir or a container and subsequently drawn off and thus completely removed from the lubricating system.

While the foregoing objects are paramount, other and lesser objects will become manifest as the description proceeds taken in connection with the appended drawing wherein:

Figure 1 illustrates the preferred form of the invention in vertical cross-section, showing the reservoir into which the impurities are deposited and the separating chamber in the upper portion thereof.

Figure 2 is a plan view of the invention showing a portion of the cover plate cut away and illustrating the rotor.

Figure 3 is a plan view of the rotor showing the radially disposed vanes arranged around the periphery thereof and the arrangement of spiral blades radiating from the axis of the said rotor.

Figure 4 is a perspective illustration of the separating chamber showing the rotor positioned therein and illustrating the series of apertures arranged around the lower wall of the chamber, and

Figure 5 is a schematic illustration of the invention attached to a conventional motor and installed in the lubricating system.

Accordingly, therefore, the invention comprises a preferably cylindrical reservoir or container 1 having an outwardly extending flange 2 around its upper rim, as illustrated in Figure 1. The bottom of the reservoir 1 is slightly concave in order to properly drain fluids therefrom through a drain valve 3 threaded into a boss 4 integral with the bottom of the reservoir 1.

A pan or cup 5, provided with an outwardly extending flange around its upper rim, and of somewhat lesser diameter than the interior circumference of the reservoir 1, is inserted into the top of the latter and allowed to depend thereinto, the flange 6 being supported by the circular flange 2 of the reservoir 1. A series of apertures 7 are arranged around the wall of the member 5, forming communications between the interior of the member 5 and the interior of the reservoir 1. The apertures 7 are arranged in the walls of the pan 5 at the bottom thereof. The member 5 is illustrated in perspective in Figure 4.

Arranged for rotation within the member 5 a rotor 8 is provided which is pivoted centrally in the bottom of the member 5, as illustrated in Figure 1, by a pin 9 adapted to be threaded into a boss 10 depending below the bottom of the pan 5. The rotor 8 has an integral hub 11 projecting upwardly centrally of the member 8 affording a suitable bearing therefor. The rotor 8 is formed with a plurality of radially arranged vanes 12 which have been previously cut from the outer rim of the member 8 and turned upwardly at right angles with respect thereto, as illustrated particularly in Figure 4.

The rotor 8, being pivoted at 9 in the bottom of the pan 5, is free to rotate when impelled by a stream of fluid, or the like, projected through a nozzle 13 having a relatively small jet in the discharge end thereof and which is directed tangentially with respect to the inner wall of the pan 5, as illustrated in Figures 1 and 2. The nozzle 13 is arranged preferably in one edge of a cover plate 15 adapted to be secured by screws 16.

or other medium, to the annular flanges 2 around the upper rim of the reservoir 1. The screws 16 are adapted to extend through the flange 6 of the member 5 and therefore retain this element in position. It will be noted that, by reason of the fact that the member 5 is of lesser diameter than the internal diameter of the reservoir 1, this member assumes a concentric position with respect to the reservoir 1 and an annular space *a* is provided therearound. The apertures 7 are adapted to communicate with the annular space *a*, as shown in Figure 1.

The boss 13, therefore, is provided with an integral hood 17 which is interiorly threaded to receive an oil line 18 communicating with the crankcase of a motor 19, as schematically illustrated in Figure 5. The cover plate 15 is provided with central bosses 20 and 21, as illustrated in Figure 1, the upper boss 20 being interiorly threaded and adapted to receive the outlet lubricating line 22, illustrated in Figure 5, and which also communicates with the crankcase of the motor 19 and conveys the lubricant back through the said motor. The boss 21 projects downwardly from the underside of the cover plate 15 and is exteriorly threaded to receive a nut 23 retaining a downwardly and concentrically arranged baffle 24. The baffle 24 is circular in formation and extends downwardly around the pivot 9 of the member 8. The member 24 has an integral annular baffle plate 25 secured to its lowermost rim.

The rotor 8 is also provided with a plurality of spirally arranged blades 26, illustrated in Figure 3, which extend downwardly from the pivot 11 terminating in certain of the recessions 27 around the periphery of the rotary member 8 and which are formed by cutting out the vanes 12 which have heretofore been referred to. The spiral blades 26 are of such depth as to be disposed for operation beneath the horizontal plate 25, illustrated in Figures 1 and 2.

In operation, the lubricant through the medium of the conventional fuel pump is circulated from the crankcase of the motor 19 through the conduit 18 and the nozzle 13 and is projected against the vanes 12 of the rotor 8 causing the latter to rotate within the pan 5 which forms a separating chamber 28 within the upper portion of the reservoir 1. The lubricant passing into the chamber 28 through the nozzle 13 in the orifice 14, upon entering the chamber 28, will receive a centrifugal separating action within the chamber 28 by the spirally arranged blades 26 previously described. The blades 26, by reason of their form and arrangement, direct the fluid outwardly against the wall of the member 5 and through the apertures 7 therein allowing the heavier constituents of the lubricant to be precipitated to the bottom of the reservoir 1. The circulation of the lubricant is completed by passing beneath the horizontal baffle 25 and up into the circular depending baffle 24 and out through the bosses 20 and 21 and the conduit 22 back into the crankcase of the motor 19. The action, therefore, to which the influent is subjected separates out the heavier particles of sand, grit, motor cuttings, and the like, as well as water and undesirable fluids becoming commingled with the lubricant in the crankcase.

At desirable intervals fresh oil may be introduced into the assembly through a pillar opening 29 normally closed by a plug 30 in the cover plate 15. The sludge and undesirable properties of the oil which are deposited in the bottom of the

reservoir 1 may be drawn off through the drain cock 3, previously described.

Obviously, the baffling arrangement 24 and 25 may be of a form in which the horizontal portion of this member is eliminated. It is desirable, however, to form the baffling assembly so that a sufficient baffling surface is presented to the liquid to insure the complete separation, in cooperation with the spiral blades 26, of the injurious constituents of the lubricant from the liquid and cause the same to be drawn out by centrifugal action through the apertures 7 and be permitted to precipitate into the reservoir 1, as previously described.

Manifestly, the structure herein shown and described is capable of considerable changes and modifications from time to time by those skilled in the art and such changes and modifications as may be resorted to which may be considered as falling within the spirit and intent of the invention may also be considered as falling within the scope of the appended claims.

What is claimed is:

1. In a decarbonizer for lubricants for internal combustion motors, a reservoir having a receptacle arranged in its upper portion, providing a separate chamber, communications in the said chamber with the reservoir, a rotor having radially disposed peripheral vanes operatively arranged in the said chamber, means comprising an inlet nozzle in the said chamber adapted to direct a stream of oil tangentially against the said vanes, a plurality of spirally disposed blades forming a part of the said rotor, the said blades imparting a centrifugal action to the lubricant outwardly and a baffled oil outlet arranged above the axis of the said rotor.

2. In a decarbonizer for lubricants for internal combustion motors, including a reservoir having a receptacle arranged in the upper portion thereof forming a chamber and communicating with the said reservoir, a rotor mounted in the said chamber, a plurality of vanes radially disposed around the periphery of the said rotor, an inlet nozzle in the top of the assembly arranged to direct an influent against the said vanes to rotate the said rotor, a series of spirally arranged blades integral with the said rotor and extending outwardly from the axis thereof directing the influent outwardly and depositing the impurities into the said reservoir and a baffled oil outlet above the axis of the said rotor.

3. In a purifier and accelerator for lubricants for internal combustion motors, a reservoir having a receptacle forming a separating chamber in the upper portion thereof communicating with the said reservoir, a rotor having a plurality of radially disposed vanes operatively arranged in the said chamber and adapted to be rotated by a stream of oil projected thereagainst, an influent nozzle arranged to direct a stream of oil into the said chamber against the said vanes, a plurality of spirally arranged blades extending outwardly from the axis of the said rotor imparting a centrifugal action to the said influent outwardly against the walls of the said chamber and depositing the heavier constituents of the said influent into the said reservoir and a baffled outlet for the said oil injected into the said chamber arranged above the axis of the said rotor.

4. In a device for separating abrasives and other impurities from lubricants in internal combustion motors, a reservoir adapted to receive the said impurities having a separating chamber formed by a receptacle arranged in the upper

portion thereof communicating with the said reservoir, a rotor operatively disposed in the said chamber having a multiplicity of vanes arranged peripherally thereon, an oil inlet nozzle arranged in the top of the said chamber to direct a stream of oil against the said vanes to rotate the said rotor, a series of spirally disposed blades extending from the axis of the said rotor outwardly toward the walls of the said chamber to impart a centrifugal urge to the influent and a baffled outlet for the said oil axially arranged above the said rotor.

5. In combination with a lubricating system for internal combustion motors, an oil purifier and accelerator comprising a reservoir adapted to receive the impurities of the said lubricant having a cup forming a separating chamber arranged in the upper portion thereof, communications between the said chamber and the said reservoir around the walls of the said chamber, a rotor having a plurality of radially disposed vanes arranged in the said chamber, an influent nozzle arranged in the top of the said chamber to direct a stream of oil against the said vanes for rotating the said rotor, means integral with the said rotor imparting a centrif-

ugal action to the influent and directing the same outwardly against the walls of the said chamber and a baffled outlet arranged axially of the said rotor for the said oil in the said system.

5. In combination with a lubricating system for internal combustion motors, a decarbonizer for purifying and accelerating the said lubricant comprising a reservoir having a depending cup forming a separating chamber arranged in the upper portion thereof, communications between the said chamber and the said reservoir, a rotor having a plurality of radially disposed vanes operatively arranged in the said chamber, an influent nozzle disposed in the upper portion of 10 the said chamber to direct a stream of influent against the said vanes to operate the said rotor, a plurality of spiral blades extending outwardly from the axis of the said rotor to direct the influent centrifugally outwardly against the walls 15 of the said chamber and toward the said communications whereby the heavier constituents of the said influent can be deposited in the said reservoir and a baffled outlet for the lubricant arranged axially of the said chamber and in the 20 top thereof.
